UNITED STATES PATENT OFFICE.

HERMAN GARRISON, OF CHICAGO, ILLINOIS:

CAN OPENER.

Application filed December 19, 1922. Serial No. 607,819.

To all whom it may concern:

Be it known that I, HERMAN GARRISON, a citizen of the United States, residing at Chicago, in the county of Cook and State 5 of Illinois, have invented certain new and useful Improvements in Can Openers, of which the following is a specification.

The present invention is related to my co-pending application, Serial Number 505, 10 615, filed on the 5th day of October, 1921, for Letters Patent for improvements in can openers, on which an essential claim has been allowed, and has for its objects similar ones to those set forth in said pending 15 application.

The principal object of either invention may be briefly stated, to provide means by which a circular cutting can opener may be operated with the knife thereof placed 20 at such an inclination with respect to the surface of the can in which the incision is to be made, as will produce the maximum ease in cutting. This object is not attained until the knife is slanted beyond 25 the position in which it is practicable to pry it into the can. In the device which is the subject of my said pending application, the problem is solved by pivoting the 30 knife to the handle, making it capable of assuming one position for piercing and another for cutting.

In the present invention, the solution consists, in one form thereof, in providing a lateral piercing prod. This prod is forced 35 into the can and then withdrawn; the handle given a partial turn and the slanting knife is thrust into the incision made by the prod, the process of opening the can being completed by the rotation of the 40 handle.

In another and the simplest form of the present invention, the handle is provided with a terminal piercing prod and a slanting cutter. As is usual in can openers of 45 this class, the center of the can is perforated by the point of said terminal prod; the handle, employed as a lever whose fulcrum is at the center is lowered, forcing the cutter into the can, and a circular cut is effected 50 by rotating the handle about the center.

In the accompanying drawings,

Fig. 1 is a view in side elevation of a can opener embodying the simplest form of the invention.

55 Fig. 2 is a bottom plan view thereof.

Fig. 3 is an end view looking towards

the end of the handle from which the terminal piercing prod is extended.

Fig. 4 is a fragmental side view of the form of opener shown in Fig. 1 but illustrating a slight modification in the form of the terminal piercing prod.

Fig. 5 is a side view of a portion of the handle of the opener illustrating a modification in the position of the terminal 65 piercing prod thereon.

Fig. 6 is a side view illustrating still another modification in the construction of the opener.

Fig. 7 is a bottom plan view thereof. 70

Fig. 8 is an end elevation of Fig. 6 looking towards the end of the handle from which the terminal piercing prod is extended.

Fig. 9 is a cross-sectional view of the 75 lateral prod of the opener of the construction shown in Figures 6 to 8 inclusive.

Fig. 10 is a similar view of a like part showing a modification in the construction thereof.

Fig. 11 is a side view of a portion of the handle and a part of the terminal piercing prod showing a modification in the construction of the cutter.

Fig. 12 is a diagrammatic view of a portion of a can showing an improperly formed puncture or opening therein. 85

Fig. 13 is a diagrammatic view of a portion of a can illustrating a part of the device and the relation of its cutter with respect to the improperly formed incision, for the purpose of assisting in an explanation 90 of the proper relation between the lateral prod and the cutter.

Fig. 14 is a diagrammatic view showing 95 a portion of another modified form of the cutter illustrating its relation with respect to the incision in the can.

Fig. 15 is a diagrammatic view of a portion of a can showing a modification in the 100 form of the incision therein.

Fig. 16 is a diagrammatic view of a portion of a can showing a portion of the opener in a position it may be caused to assume in the operation of opening cans of unusual 105 size or shape, and

Fig. 17 is a side view of a portion of the handle and a portion of the terminal prod of the instrument showing a modification in the mounting of the cutter on the handle and the provision of a guiding shoulder to engage the rim of the can. 110

Corresponding numerals of reference refer to like parts throughout the different views of the drawings.

Referring now more particularly to Figs. 5 1 to 3 inclusive of the drawings, the numeral 20 designates the handle of the device, which may be made of any suitable size, shape and material, but has rigidly fixed to its front end and extended longitudinally therefrom, 10 a terminal piercing prod 21 which as shown in Figs. 1 and 2 is aligned with the handle and of a straight forwardly tapered form. However, this terminal prod may be of the modified form shown at 22 in Fig. 4 of the 15 drawings, in which view it will be observed that the prod is slightly arcuate, or, instead of being located in alignment with the handle as shown in Figs. 1 and 2, it may be disposed at an angle to the handle as shown at 23, in 20 Fig. 5 of the drawings, either of which modifications will facilitate longitudinal movement of the prod. By varying the depth to which the prod is inserted in the center of the can, the instrument can be adapted to the 25 most common sizes of cans, varying in diameter from two and a half to four inches.

As shown in Figs. 1, 4, 6, 11, 13 and 16 of the drawings, the knife or cutter which is designated as a whole in each of said views 30 by the numeral 24, is rigidly fixed to the handle near the end thereof adjacent the terminal piercing prod at an angle thereto, and has on its front face near the handle a shoulder 25 which acts as a brace and also 35 for a purpose in the operation of the opener to be presently explained. The average housewife will find it difficult to make a draw cut on any can of greater diameter than about $3\frac{1}{4}$ inches, not only because the larger 40 can is of thicker material, but because, no matter how easily the knife may cut, she cannot grasp the can with one hand while using the other to operate the instrument. For this reason commercial openers of this 45 class are always provided with an extra knife to be used in prying. In this opener one knife serves both purposes, as shown in Figure 16. The shoulder 25, resting on the rim of the periphery affords a fulcrum for 50 prying, and the operator, by alternately pulling the handle toward him and moving the instrument forward will accomplish successive stages of the work of cutting.

The knife or cutter 24 is pointed as shown, 55 and is mounted on the handle transversely with respect thereto. This construction and arrangement of the knife or cutter 24 is maintained in the construction of the device wherein a terminal piercing prod only is 60 employed, as well as in the construction wherein a lateral piercing prod as well as a terminal prod is employed.

The length of the knife, measured from 65 its base or point of attachment to the handle, is much greater than is usual in openers of

this type, and its continuation beyond the shoulder 25 exceeds the length required for a draw cut. The primary object of this elongation of the knife is to increase the angle which it will form with the surface at the 70 moment of insertion, thus facilitating its introduction into the can. In the softer material of the smaller cans this can usually be accomplished without having recourse to the lateral prod 26 to effect an initial opening. 75

The lengthening of the knife is also of use in adapting the instrument to cans of different sizes, and it assists in the process of raising the partially detached segment of the top of the can after the incision is completed. This is accomplished very readily by a twist of the handle, which forces the knife against the lower side of the segment.

The modified form of the opener shown in 80 Figs. 6 to 8 inclusive consists in employing the cutter 24, the terminal prod 21, and in addition thereto a laterally extended prod 26 which is located near the end of the handle 20 adjacent the prod 21, and is by preference slightly inclined in a forward 85 direction as shown in Fig. 7 of the drawings.

In order to establish a proper relation 90 between the cutter 24 and the lateral prod 26, it should be understood that the prod 26 must be thick enough to make an opening when forced into the surface of the can in which the incision is to be made, of sufficient width, measured on a radius of the can, to admit the point of the slanted knife. This width may be attained by making the 95 forward face of the prod 26 plane and the back thereof obtuse as at 27, see Fig. 9 of the drawings, or by making the forward face of the prod 26 plane and the back thereof convex as at 28, see Fig. 10 of the 100 drawings. By this arrangement it is manifest that when the prod 26 is forced into the top 29 of a can 30, the bent portions 31 and 32 of the can, see Fig. 14, will be 105 caused to assume about the positions shown in the last named figure of the drawing, and that the bent portion 31 will be greater than the bent portion 32. It will further be understood that the plane front face of the prod is slanted forward as far as practicable, thus giving a like slant to the bent portion 32 of the can. The point of the 110 cutter 24 may be truncated as shown at 33 in Fig. 14, or may be convex or arcuate on top, or may even be bent down as shown at 115 34 in Fig. 11 of the drawings. The construction shown in Fig. 17, at 33 and 34 will facilitate the introduction of the knife into the can when the prod 26 is not employed, since it will cause the point to strike the surface in a more nearly vertical direction.

In order to assist in a explanation of the 120 mutual co-action of the lateral prod, the cutter, and the bent portions of the can, dia- 125

grammatic views of the can are shown in Figs. 12 to 15 inclusive, in the former of which views the top of the can 30 is shown as being provided with a puncture produced by a prod occupying a position with respect to the top of the can whereby the bent portions 31 and 32 of the puncture are caused to assume substantially vertical positions as shown. The same positions of the bent portions 31 and 32 are shown in Fig. 10

13, in which view the can opener is shown in operative position to illustrate the improper relation of the bent portions of the can to the cutter.

15 In Figs. 14 and 15 the bent portions 31 and 32 of the can are shown in about the positions they will assume when it is desired to insert the cutter in the puncture for operation of the opener.

20 In Fig. 16 of the drawings, I have shown the opener occupying a position it is adapted for when designed for use on cans of unusual size or shape, from which view it will be understood that by thrusting the 25 cutter 24 into the can vertically, the shoulder 25 will rest on the rim of the can and furnish a fulcrum on which the cutter may be pried forward, in a like manner as with openers of the ordinary type.

30 In Fig. 17 is illustrated a modification which consists in providing the handle 20 of the cutter with a block 33 from which the cutter is forwardly inclined and providing said block with a shoulder 34 rearwardly of the cutter to rest on the rim of the can 30 for the purpose of acting as a 35 stop or guide to prevent inward movement of the cutter when the handle is rotated.

By employing a can opener embodying 40 my improvements, I have found by practical experiments that it cuts much more readily than the openers in which a draw cut is made with a knife which is nearly vertical. The reason is, that when the cutter is vertical or but little slanted, the cut edges of the tin must be bent as is shown in 45 Figs. 12 and 13, whereas with a greater slant, the labor required to bend the tin is avoided as shown in Fig. 15 of the drawings.

Having thus fully described my invention, what I claim as new and desire to secure by Letters Patent is—

1. In a can opener the combination of a 55 handle, a terminal tapering prod which extends obliquely downward, and secured to the handle an elongated transverse cutting

knife, which is set obliquely forward with reference to the axis of the handle and which maintains its oblique direction 60 throughout its entire length.

2. In a can opener the combination of a handle, an elongated transverse cutting knife which is secured to said handle and set obliquely forward with reference to the 65 axis thereof, and which maintains its oblique direction throughout its whole length, and a terminal tapering prod which is deflected toward a position parallel to the 70 knife, the minimum length of the deflected element being such as to approach in magnitude the length of the elongated knife.

3. In a can opener the combination of a handle terminating with a pointed tapering prod which extends obliquely downward, and secured to the handle an elongated transverse knife having both its cutting blade and its point set oblique to the 75 axis of the handle; the divergence of direction between the handle and the point being greater than that between the handle and the basal part of the cutting knife.

4. In a can opener the combination of a handle, an elongated knife secured thereto, and having both its cutting blade and its 80 point set oblique to the axis of the handle, a tapering terminal prod which extends obliquely downward to a distance whose minimum approaches the length of the knife, and a shoulder adjacent and anterior to the 85 base of the knife and facing toward the pointed end of the instrument.

5. In a can opener the combination of a handle, a tapering terminal prod which extends obliquely downward, an elongated 90 knife which is secured to the handle and set oblique to the axis thereof, its oblique direction being continued throughout its entire length; and a shoulder situated within the apex of the plane angle defined by the 95 inner faces of the knife and handle and adapted to rest on the periphery of the can when the knife is inserted vertically with the prod outside the can.

6. In a can opener the combination of a 100 handle, a terminal tapering prod which extends obliquely downward, an elongated transverse cutting knife which is secured to the handle and is forwardly inclined, the 105 inclination of its point being less than that of its basal portion, and a shoulder placed anterior to the base of the knife and facing toward the pointed end of the instrument.

HERMAN GARRISON.
